[57] CLAIM

The ornamental design for a golf ball retriever, as shown and described.

DESCRIPTION

FIG. 1 is a perspective view of a golf ball retriever showing our new design with a fragmentary broken line showing of a handle for illustrative purposes only.

FIG. 2 is a bottom view of the retriever of FIG. 1.

FIG. 3 is a side view of the retriever of FIG. 1.

FIG. 4 is a rear view of the retriever of FIG. 1.

FIG. 5 is a front view of the retriever of FIG. 1.

FIG. 6 is a top view of the retriever of FIG. 1.

FIG. 1.

FIG. 2.

FIG. 3.

FIG. 4.

FIG. 5.

FIG. 6.
